CIRCUIT INTERRUPTER

Herbert L. Rawlins, Wilkinsburg, Pa., assignor to
Westinghouse Electric & Manufacturing Com-
pany, East Pittsburgh, Pa., a corporation of
Pennsylvania

Application April 8, 1933, Serial No. 665,132

31 Claims. (Cl. 200—120)

My invention relates to circuit interrupters and particularly to high voltage expulsion fuses.

One object of my invention is to provide a refillable high voltage expulsion fuse that shall be 5 simpler in design, more economical to manufacture, and more satisfactory and more reliable in operation than the previously known devices of this general type.

Another object of my invention is to provide 10 an improved refill element for use with expulsion fuses, my improved refill element to be inexpensive to manufacture and simple to install.

A further object of my invention is to provide 15 an improved high voltage expulsion fuse which shall include at least two separate arc passages and means for establishing an arc in each of the passages, the arc interrupting capacity of the two passages being different in order that the fuse may be equally effective for both high and 20 low values of arc current.

A further object of my invention is to provide 25 an improved expulsion fuse of the double arc passage type which shall include means for establishing one of the two arcs at a time subsequent to the establishing of the other arc.

A further object of my invention is to provide 30 an improved lining for the arc passage of an expulsion fuse, my improved lining to liberate a large volume of non-inflammable arc-extinguishing gas, substantially all of which is of inorganic composition, when placed in proximity to an electric arc, and to include means for strengthening those parts of the lining which may be 35 mechanically weak.

A still further object of my invention is to provide 40 an improved expulsion fuse which shall utilize an fuse link of small dimensions positioned adjacent the open end of the fuse closure, and which shall include means for drawing the arc within the closure during the extinguishing operation.

One field for immediate application of my invention is in connection with high voltage expulsion fuses that utilize boric acid as the source 45 of the arc extinguishing gas, and I shall herein-after describe an embodiment of my invention as applied to such devices, without, however, in any way intending to restrict the scope of my invention except as indicated in the appended invention except as indicated in the appended 50 claims.

In this type of fuse, a short fusible link is connected to the lower end of a movable rod or plunger, the other end of the rod being affixed to a piston member of conducting material which 55 is disposed within an insulating tube and is

biased upwardly by a coil spring. A flexible conducting shunt disposed within the coil spring completes the electrical circuit to the stationary contact. Upon the fusion of the link, the rod moves upwardly, under the influence of the biasing spring, and establishes the arc within a chamber that is lined with boric acid. The boric acid decomposes and the resulting outwardly flowing vapor, substantially all of which is superheated steam, extinguishes the arc.

The fuse is restored to an operative condition following each circuit interrupting operation by the removal and replacement of the refill element which includes the boric acid lining for the arc passage, the movable plunger, and the fuse assemblage. From this, it is immediately apparent that the refill operation consists in the replacing of all of the parts which are subjected to the action of the arc, thereby assuring continued reliable operation of the device.

The features of my invention which I believe to be new are particularly pointed out in the appended claims. For a fuller understanding of the principles of the invention and the best mode of applying those principles, reference may be had to the accompanying drawings, in which;

Fig. 1 is a side view, partially in section, of an expulsion fuse embodying the principal features of my invention.

Fig. 2 is an enlarged sectional view of a refill element for use with the expulsion fuse shown in Fig. 1.

Fig. 3 is a sectional view similar to Fig. 2 showing a modified form of refill unit.

Fig. 4 is an enlarged sectional view on the line IV—IV of Fig. 1.

Fig. 5 is an enlarged end elevation of the expulsion fuse shown in Fig. 1.

Fig. 6 is an end elevation of one of the refill units shown in Figs. 2 and 3.

Fig. 7 is a fragmentary sectional view showing the method of connecting the refill element and the movable piston member.

Fig. 8 is an end elevation of the fuse structure shown in Fig. 1 and illustrates the method used for supporting the operating spring.

Fig. 9 is a fragmentary sectional view showing the structural details of the upper end of the fuse shown in Fig. 1.

The expulsion fuse shown in Fig. 1 includes a cylindrical fibre tube 1, having relatively heavy side walls and threaded ends 3 and 5, and two tubular terminal caps 7 and 9 which have internally threaded portions for engaging the threaded ends 3 and 5 of the main fibre tube 1.

- The terminal caps are each provided with contact surfaces 11 for engaging suitable contact jaws (not shown). The upper terminal cap 7 is provided with an annular recess 13 for engaging 5. the upper portion of the outer tube 15 which is preferably of porcelain or glass, or other weather-proof insulating material. A projecting shoulder 17 on the lower terminal cap 9 holds the porcelain tube 15 within the annular recess 13, suitable washers 19 and 21 of cork or like material being provided for preventing undue stress being placed on the porcelain tube 15 and to make the joint watertight. The upper end of the fuse is closed by means of a cap member 23 which, as 10 will be described in some detail later, engages the support means for the main operating spring 25.
- The working parts of the fuse include the main operating spring 25 which is provided with a support member 27 at one end and which engages 20 the piston member 29 at the other end, the flexible conducting shunts 31 disposed within the main operating spring 25 and electrically connected to the spring engaging members 27 and 29, as shown particularly in Figs. 7 and 9, and 25 the refill element 33 which engages the piston member 29. The lower end of the refill element 33 is provided with a ferrule 35 which is adapted to abut against a shoulder 37 forming a part of the lower terminal cap 9. A hollow cylindrical member 39 having a threaded side portion 41 is provided for engaging the threaded end 43 of the lower terminal cap in order to retain the refill element 33 in position and to assure a good electrical contact between the ferrule 35 and the lower terminal cap 9 itself.
- The preferred form of the refill element 33 is shown particularly in Fig. 2. It includes a fibre tube 45 having side walls of considerable mechanical strength and a threaded end 47 for 40 engaging the metallic ferrule 35. The fibre tube 45 is lined for the greater part of its length with a cylindrical liner member 49 of boric acid. The boric acid lining has a cylindrical passage 51 through the center in order to accommodate 45 the rod or plunger 53, and is further provided with a second passage 55 of considerably smaller cross sectional area than the passage 51.
- A threaded fibre plug 57 having an opening 59 therethrough is provided for engaging the 50 upper end of the boric acid lining 49, an insulating washer 58 being interposed between the plug 57 and the lining to equalize the stresses. The lower end of the central passage 51 terminates in a conical throat 60, the lower portion of which 55 is defined by a fibre plug 61, it being necessary to provide a material of greater mechanical strength than boric acid for lining those portions of the throat where the thickness of the lining becomes small. The ferrule 35 is provided with an opening 63 which forms a continuation of the central passage 51 and the throat 60, and an annular shoulder 65 which abuts against an insulating washer 67 to retain the lining 49 within the tube 45.
- 65 The cylindrical plunger or rod member 53 is preferably of copper; the lower end 68 includes an opening (not shown) for permitting one end of the fusible link 69 to be soldered thereto, the other end of the fusible link 69 being electrically connected to the ferrule 35 by means of a screw 71. The upper end 70 of the plunger rod 53 is threaded for engaging the piston member 29, and is provided with a positioning pin 73 extending therethrough substantially at right angles to the longitudinal axis of the plunger. This

pin 73, as shown particularly in Fig. 6, cooperates with two diametrically opposed slots 75 in the top portion of the fibre tube 45 of the refill unit 33 in order to prevent rotation of the plunger with respect to the other parts of the refill unit, 80 during the refilling operation.

In the modification of the refill unit 33 shown in Fig. 2, a wire 77 of somewhat smaller cross sectional area than the cross sectional area of the smaller passage 55 through the boric acid lining 49 is securely affixed to the upper end 70 of the plunger rod 53 and extends downwardly into the passage 55 where it slidably engages a similar wire 79 extending upwardly into the passage 55 for about one-third of its length. The lower end of the wire 79 is retained in position within a recess in the fibre throat lining member 61 and is not electrically connected to the ferrule 35.

The modification of the refill unit 33 shown in Fig. 3 is similar to the structure shown in Fig. 2 except that a single wire 81, rigidly affixed to the plunger 53 at the upper end thereof, extends through the passage 55, the lower end of the wire 81 engaging a suitable recess in the 100 throat lining member 61 and being therein retained by the insulating washer 67. The wire 81 includes a coil portion 83 for providing a lost motion connection between the portion within the passage 55 and the portion affixed to the 105 plunger rod 68. Thus, when the plunger 68 is moved upwardly by the piston member 29, the wire 81 does not move to establish an arc within the passage 55 until a time subsequent to the establishing of the arc in the central passage 110 53. In the modification shown in Fig. 2, this time delay is secured by means of the sliding engagement between the wire 77 mechanically connected to the moving plunger 53 and the other wire 79. The current carrying capacity of the 115 wires 77 and 78 is limited in order that they may fuse upon the passage therethrough of current of a predetermined magnitude, this arrangement facilitating the interruption of high current arcs.

The lower end of each of the refill units 33 is closed by means of a frangible disk 85 of insulating material. This disk 85 is adapted to break immediately upon the building up of any appreciable gas pressure within the unit, and, while it 125 completely seals the vent end of the refill it in no way interferes with the normal expulsion action of the device.

The piston member 29, as is shown particularly in Figs. 1 and 7, include a body portion 87, a 130 threaded opening 89 for engaging the threaded end 70 of the refill element 33, a similar threaded opening 91 at the upper end for engaging the screw 93 which cooperates with a wedge member 95 to fasten the conducting shunts 31 135 to the body portion 87, and a threaded means 97 on the outer surface for securely engaging one end of the operating spring.

The spring supporting member 27, includes a threaded means 99 for engaging the upper end 140 of the operating spring 25, a threaded opening 101 for engaging the screw 103 which, in combination with the wedge member 105, retains the shunts 31 in mechanical and electrical connection with the spring supporting member itself, 145 and, in addition, it includes a threaded end portion 107 having a pin 109 extending therethrough (Figs. 8 and 9). This threaded end portion 107 cooperates with the cap member 23 in order to hold the spring 25 in the tensioned or operative 150

position and, at the same time, permits the establishing of a low resistance electrical connection between the upper end of the shunts 31 and the upper terminal cap 7, the spring supporting member 27 having a shoulder 111 which cooperates with a similar shoulder 113 on the inside of the upper terminal cap 7.

The fuse is shown in the closed circuit position in Fig. 1. It will be noted that the main operating spring 25 is tensioned so as to bias the piston member 29 toward the upper terminal cap 7. This biasing force is transmitted through the plunger 53 and must be balanced by the fusible element 69. Upon the occurrence of an overload condition in the controlled circuit, the fusible link 69 melts, thus releasing the lower end 68 of the plunger 53 and permitting that member to move upwardly into the central arc passage 51 under the biasing action of the main operating spring 25. An arc is immediately established between the end 68 of the plunger 53 and the ferrule 35. This arc will practically immediately contact the lower end of the wire 79 thereby putting the conductors 77 and 79 within the smaller of the two arc passages in parallel with the arc. If the current to be interrupted is of small magnitude, the immediate result will be an extinction of the arc in the central passage 51 at the first zero point, all of the current flowing through the conductors 77 and 79, and further upward movement of the plunger 53 will then result in a separation of the two wires 77 and 79 which are in slidably conductive relationship. A second arc will thereby be established within the smaller arc extinguishing passage 55 and, since that passage is particularly adapted for extinguishing small arcs, the out-flowing superheated water vapor will cause a very rapid cooling and extinguishing of the arc.

If the magnitude of the arc current is such as to cause an immediate fusing of the conducting means within the smaller arc passage 55, the arc will persist in the larger passage 51, although the extinguishing operation is essentially the same, the heat of the arc causing the boric acid lining 49 to evolve superheated steam which flows outwardly longitudinally of the arc through the throat opening 60, the opening 63 in the ferrule, and the continuation of that opening in the lower portion of the terminal cap 9 and the hollow cylindrical member 39.

One method utilized in the past to secure interruptions of small current arcs in expulsion fuses utilizing the double arc passage construction was to provide a fusible wire, having a lower rating than the main fusible element within the smaller arc passage. This structure was not entirely satisfactory, however, because when the fuses were used on high voltage circuits the destructive effect of corona upon the smaller diameter fuse wires resulted in a very definite limiting of the minimum value of arc current which could be interrupted, that value for usual distribution voltage being somewhere around 40 amperes. With my invention, however, a positive mechanical opening of the electrical circuit within the smaller of the arc passages is secured, whether the conducting means disposed therein fuses or not, and it is possible thereby to interrupt arc currents of practically any range. In this connection, it is important to note that it is not possible to satisfactorily interrupt low current arcs in the larger arc passage due to the absence of means for bringing the arc into intimate

contact with the gas evolving lining of the arc passage.

The operation of the modification shown in Fig. 3 is essentially the same as the operation of the structure shown in Fig. 2, except that the establishment of the arc in the smaller arc extinguishing passage 55 is caused by the mechanical movement of the lower end of the wire 81 from its engagement with the fibre lining member 61 and the drawing of the wire 81 through the smaller passage. The coil portion 83 of the wire 81 makes possible a time delay between the fusing of the main fusible element 69 and the drawing of the arc in the smaller arc passage 55.

Following each circuit interrupting operation of the expulsion fuse, it is necessary to restore the device to an operative condition. This is accomplished in the preferred embodiment of my invention by the replacing of the refill element 33, thereby renewing all of the parts of the fuse which come in contact with the arc and which may thereby be damaged. The refill element 33 is relatively inexpensive, however, due to its simple structure, and while it makes possible the restoration of the fuse to a potential effectiveness equal to that when new, the cost of so doing is much less than the cost of restoring any of the previously known high voltage expulsion fuses to an operative condition.

In the open circuit position, the plunger member 53 has been moved by the operating spring 25 a sufficient distance toward the upper end of the fuse to draw the end of the plunger to the top of the central arc extinguishing passage 51. The first step in the insertion of a new refill element 33 consists in the unscrewing of the cylindrical retaining member 39 which screws into the lower portion of the terminal cap 9. The fibre tube 45 which forms the body portion of the refill element 33 and its attached ferrule 35 are then free to drop out, leaving only the plunger 53 within the fuse tube. In order to remove the plunger 53 and to reinsert the new refill element, the cap member 23 on the upper terminal cap 7 is unscrewed from the threaded portion 110 of the spring supporting member 27, rotation of that member being prevented by the engagement of the pin 109 with the slot 115 in the top of the upper terminal cap 7.

Following the removal of the cap 23, the spring 125 supporting member 27 may be lifted upwardly and turned in a counterclockwise direction (Fig. 8) so that the pin 109 alines with the slotted openings 117 extending entirely through the upper portion of the terminal cap 7. The spring 130 supporting member 27, the spring 25, the piston member 29, the associated shunts 31, and the plunger 53 which is screwed into the piston member 29 may then be removed from the lower end of the fuse mechanism. The next step is the removal of the plunger 53 from the piston member 29. Following this, a new refill element 33 is screwed securely into the piston member 29, the pin 73 preventing rotation of the plunger member 53 with respect to the body portion of 140 the refill element. The connected refill element and plunger moving mechanism are then inserted in the lower end of the fuse and the cylindrical retaining member 39 is tightened so as to securely hold the ferrule 35 of the refill element 33 against the cooperating shoulder 37.

In order to tension the spring 25, it is now necessary to insert a means for engaging the spring supporting member 27 into the fuse through the opening 119 in the upper terminal 150

cap 7, the simplest device being a rod having a suitable threaded end for engaging the threaded hole 121 in the top of the spring supporting member 27. The rod or other means for engaging the 5 spring supporting member 27 is screwed into the threaded opening 121 and the spring supporting member 27 is then pulled upwardly toward the top terminal cap 7, it being necessary to align the pin 109 with the slots in order to draw the 10 threaded portion 107 of the member 27 through the opening 119. The spring support member 27 is then rotated in a clockwise direction in order to permit the reengagement of the pin 109 with the stops 123 which prevent that member from 15 disengaging the end terminal cap 7. The cap member 23 may then be screwed onto the threaded end 107 of the spring supporting member 27, thereby effectively closing the upper end 20 of the fuse and restoring the entire device to an operative condition.

It will thus be seen that I have disclosed an improved high voltage expulsion fuse which is of simple design and which at the same time, is capable of more satisfactory and more reliable 25 operation than the structures heretofore known to the art.

In addition, it will be seen that I have disclosed an improved refill element for an expulsion fuse which permits the replacement, at a very moderate 30 cost, of all of the parts of the fuse which are exposed to the action of the arc. Further, I have disclosed means particularly adaptable for use with an expulsion fuse having at least two arc extinguishing passages of different arc interrupting 35 capacities, whereby the arc in one of the passages may be established at a time subsequent to the establishing of the arc in the other of the passages through the use of a single, simple operating mechanism.

40 Besides these features capable of wide adaptation to the expulsion fuse art, I have disclosed certain specific forms of construction which are particularly effective in carrying out the general objects of my invention. I have shown how to 45 reinforce the lining for an arc passage with a material having greater mechanical strength than the lining itself, and I have shown a simple and effective means for connecting the operating spring of a plunger operated circuit interrupting 50 device to one of the terminals of that device.

While, in accordance with the patent statutes, I have given the foregoing details of a preferred practical embodiment of my invention, it is to be understood that many variations from the 55 precise form described are possible and may for some applications be desirable. I desire, therefore, that the language of the accompanying claims shall be accorded the broadest reasonable construction and that my invention be limited 60 only by what is explicitly stated in the claims and by the prior art.

I claim as my invention:

1. In a device for interrupting an electrical circuit, a single means having a pair of passages 65 therein, said passages each providing a path for an arc and said arc paths being arranged electrically in parallel, means for establishing an arc in one of said passages, and means, mechanically actuatable by said means for establishing an 70 arc in one of said passages, for establishing an arc in the other of said passages, one of said passages having a greater arc interrupting capacity than the other of said passages.

2. In a device for interrupting an electrical 75 circuit, a single means having a pair of passages

therein, said passages each providing a path for an arc, said arc paths being arranged electrically in parallel in the circuit to be interrupted, means for establishing an arc in one of said passages, and means, mechanically actuatable by said means for establishing an arc in one of said passages, for establishing an arc in the other of said passages at a time subsequent to the establishing of said first arc, one of said passages being most effective in extinguishing arcs of low current value and the other of said passages being most effective in extinguishing arcs of high current value.

3. In a device for interrupting an electrical circuit, a single wall defining means having a pair of passages therein, means, mechanically interconnected, for establishing an arc in each of said passages, and means for electrically connecting said arcs in parallel, one of said passages having a cross sectional area greater than the cross sectional area of the other of said passages.

4. In a device for interrupting an electrical circuit, a single wall defining means having a pair of passages therein, means, mechanically interconnected, for establishing an arc in each of said passages, and means for electrically connecting said arcs in parallel, said arc establishing means including means whereby an arc is established in one of said passages before the second arc is established in the other of said passages.

5. In a device for interrupting an electrical circuit, a single means for defining a pair of passages having rigid walls, means including a plunger and a member of conducting material, each movable in one of said passages, for establishing an arc in each of said passages, said movable plunger and said movable member of conducting material being mechanically interconnected, and means for electrically connecting said arcs in parallel, each of said passages having a cross sectional area only slightly greater than said arc establishing means movable therethrough.

6. In a device for interrupting an electrical circuit, a single means having a pair of passages 120 therein, a plunger movable in one of said passages to establish an arc therein, means movable in the other of said passages to establish a second arc in said other passage, a lost motion mechanical connection between said plunger and 125 said movable means whereby said second arc is established subsequent to the establishment of said first arc, and means for electrically connecting said arcs in parallel, one of said passages having a substantially greater cross sectional 130 area than the other of said passages, and both of said passages being lined with a solid material capable of evolving large amounts of gas when placed in proximity to an electric arc.

7. In a device for interrupting an electrical 135 circuit, means having a pair of passages therein, a plunger movable in one of said passages to establish an arc therein, means movable in the other of said passages to establish a second arc in said other passage, a lost motion mechanical 140 connection between said plunger and said movable means whereby said second arc is established subsequent to the establishment of said first arc and means for electrically connecting said arcs in parallel, both of said passages being lined 145 with boric acid.

8. In a device for interrupting an electrical circuit, means having a pair of passages therein, means mechanically interconnected, for establishing an arc in each of said passages, and 150

- means for electrically connecting said arcs in parallel, both of said passages being lined with boric acid.
9. In a device for interrupting an electrical circuit, a single means defining a pair of passages, and means for drawing an arc in each of said passages, one of said arc drawing means including means which separate to establish an arc therebetween, the other of said arc drawing means including means adapted to slidably engage a cooperating means to delay the establishing of the arc in the other of said passages until a time subsequent to the establishing of the arc by said separable means.
10. In a device for interrupting an electrical circuit, means defining a pair of passages which have rigid walls and which are lined with a solid material capable of evolving an arc extinguishing gas when placed in proximity to an electric arc, and two separate means, mechanically interconnected for drawing an arc in each of said passages, one of said mechanically interconnected arc drawing means including a pair of conducting members which separate upon the occurrence of predetermined electrical conditions in the controlled circuit to establish an arc in the first of said passages, the other of said mechanically interconnected arc drawing means including a pair of conducting members which slidably engage each other during a portion of the arc drawing operation, the slidable engagement of said other arc drawing members causing the arc in the second of said passages to be established subsequent to the establishment of the arc in the first of said passages.
11. In a device for interrupting an electrical circuit, means defining a pair of passages which have rigid walls and which are lined with a solid material capable of evolving an arc extinguishing gas when placed in proximity to an electric arc, terminal means of conducting material positioned at one end of said passage defining means, conducting means electrically connected to said terminal means and extending into the first of said passages for a predetermined distance, plunger means movable through the second of said passages to establish an arc therein, means mechanically connected to said plunger means and adapted to slidably engage said means extending into the first of said passages to establish an arc therein, and means for electrically connecting both of said arcs in parallel, the slidable engagement between said means extending into the first of said passages and said means mechanically connected to said plunger causing the arc in the first of said passages to be established subsequent to the establishment of the arc in the second of said passages.
12. In a device for interrupting an electrical circuit, means defining a pair of passages, one of said passages having a greater arc interrupting capacity than the other of said passages, terminal means positioned at one end of said passage defining means, conducting means extending into the passage of lesser arc interrupting capacity for a predetermined distance, plunger means movable through the passage of greater arc interrupting capacity to establish an arc therein, means mechanically connected to said plunger means and adapted to slidably engage said means extending into the passage of lesser arc interrupting capacity to establish an arc therein, and means for electrically connecting said arcs in parallel, the slidable engagement between said means extending into the passage of lesser arc interrupting
- capacity and said means mechanically connected to said plunger causing the arc in the passage of lesser arc interrupting capacity to be established subsequent to the establishment of the arc in the passage of greater arc interrupting capacity, both of said passages being lined with material capable of evolving large amounts of gas when placed in proximity to an electric arc.
13. In a device for interrupting an electric circuit, means partially of compressed boric acid and partially of insulating material of greater mechanical strength than boric acid, for defining a passage having rigid walls, and means for establishing an arc within said passage.
14. In a device for interrupting an electric circuit, means, partially of a solid material capable of evolving a readily condensable, inorganic gas when placed in proximity to an electric arc, and partially of insulating material of greater mechanical strength than said gas evolving material, for defining a passage having rigid walls, and means for establishing an arc within said passage.
15. In a device for interrupting an electric circuit, means of compressed boric acid for defining a passage of substantially uniform cross section and having rigid walls, said passage having an enlarged throat portion at one end, means of insulating material of greater mechanical strength than said boric acid for defining a continuation of said throat portion, and means for establishing an arc in said passage.
16. In a device for interrupting an electrical circuit; a tubular closure; a renewable refill unit which is normally positioned within said closure and which includes means defining an arc passage and conducting means movable through said passage to establish an arc therein; and means within said tubular closure for releasably engaging and actuating said conducting means movable through said arc passage.
17. In a device for interrupting an electrical circuit, a tubular closure, means for closing one end of said tubular closure, a renewable refill unit which is normally positioned within said closure and which includes means defining an arc passage and conducting means movable through said passage to establish an arc therein, spring means within said closure for moving said conducting means to establish an arc within said passage, means for releasably connecting one end of said spring means to said movable conducting means, and means for releasably connecting the other end of said spring means to said means for closing one end of said tubular closure.
18. In a device for interrupting an electrical circuit; a tubular closure of insulating material; a renewable refill unit which is normally positioned within said closure and which includes a second tubular closure, the walls of which are lined with a solid material capable of evolving large quantities of arc extinguishing gas when exposed to an electric arc; conducting means movable through said second tubular closure to establish an arc therein, and a fuse link for holding said conducting means in the closed circuit position; spring means within said first closure for moving said conducting means to establish an arc within said second closure following the release of said conducting means by said fuse link; and means for releasably connecting one end of said spring to said movable conducting means to permit the replacement of said refill unit.
19. In a device for interrupting an electrical circuit, a tubular closure of insulating material,

- a renewable refill unit which is normally positioned within said closure and which includes a second tubular closure and conducting means movable through said second tubular closure to establish an arc therein, spring means within said first closure for moving said conducting means to establish an arc within said second tubular closure, and means for releasably connecting one end of said spring means to said movable 10 conducting means, at least a portion of the inner wall of said second tubular closure being of a material capable of evolving large volumes of an arc extinguishing gas, substantially all of which is of inorganic composition, when placed 15 in proximity to an electric arc.
20. In a device for interrupting an electrical circuit; a tubular closure; removable means for closing one end of said tubular closure; a renewable refill unit which is normally positioned 20 within said closure and which includes means defining an arc passage and conducting means movable through said passage to establish an arc therein; spring means within said closure for moving said conducting means to establish an 25 arc within said passage; means for releasably connecting one end of said spring means to said movable conducting means; and means at the other end of said spring means, engageable by a tool inserted through the end of said closure 30 adapted to be closed by said removable means, to permit the stressing of said spring means and to releasably connect said other end of said spring means to said means for closing one end of said tubular closure.
35. 21. In a device for interrupting an electrical circuit, a tubular closure, means for closing one end of said tubular closure, a renewable refill unit including means defining an arc passage and conducting means movable through said passage to 40 establish an arc therein, spring means within said closure for moving said conducting means to establish an arc within said passage, means for releasably connecting one end of said spring means to said movable conducting means, and 45 means including a slotted opening in said means for closing one end of said tubular closure and rotatable means for cooperating with said slotted opening to releasably connect the other end of said spring means to said closing means.
50. 22. In a device for interrupting an electrical circuit, means defining two arc extinguishing passages, the first of said passages being capable of interrupting low values of current, the second of 55 said passages being capable of interrupting high values of current but being incapable of interrupting low values of current, conducting means including a fusible wire within said first passage, and means operable after a predetermined period of time during the circuit interrupting operation 60 to mechanically withdraw said fusible conducting means for said first passage if said fusible conducting means has not previously fused.
65. 23. In a device for interrupting an electrical circuit, means defining two arc extinguishing passages, the first of said passages being capable of interrupting low values of current, the second of 70 said passages being capable of interrupting high values of current but being incapable of interrupting low values of current, conducting means including a fusible wire within the first of said 75 passages, means, actuatable after a predetermined time during the circuit opening operation, for mechanically breaking the electrical circuit through said wire and withdrawing said wire
- from said first passage if said wire has not previously fused.
24. In a device for interrupting an electrical circuit; means for defining the walls of a pair of arc passages; one of said arc passages being capable of extinguishing arcs of large current magnitude but being incapable of extinguishing arcs of small current magnitude, and the other of said 80 passages being capable of extinguishing arcs of small current magnitude; and arc drawing means for causing the circuit when carrying currents of large magnitude to be finally interrupted in the first of said passages, and for causing the circuit when carrying currents of small magnitude to be finally interrupted in the second of said passages; said arc drawing means comprising two separate conducting means one of which is movable through each of said 85 passages to establish an arc therein, and a single means for moving both of said conducting means. 90
25. In a device for interrupting an electrical circuit; means for defining the walls of a pair of arc passages; one of said arc passages being capable of extinguishing arcs of large current magnitude but being incapable of extinguishing arcs 95 of small current magnitude, and the other of said passages being capable of extinguishing arcs of small current magnitude; and arc drawing means for causing the circuit when carrying currents of large magnitude to be finally interrupted in the first of said passages, and for causing the circuit when carrying currents of small magnitude to be finally interrupted in the second of said passages; said arc drawing means comprising two separate conducting means 100 one of which is movable through each of said passages to establish an arc therein, and a single energy storing means for moving both of said conducting means; said arc drawing means causing the circuit through said interrupter to be initially opened in said arc passage capable of extinguishing arcs of large current magnitude. 105
26. In a device for interrupting an electrical circuit; means for defining the walls of a pair of arc passages; one of said arc passages being 110 capable of extinguishing arcs of large current magnitude but being incapable of extinguishing arcs of small current magnitude, and the other of said 115 passages being capable of extinguishing arcs of small current magnitude; and arc drawing means for causing the circuit when carrying currents of small magnitude to be finally interrupted in the second of said passages; said arc drawing means comprising two separate conducting means one of which is movable through each of said 120 passages to establish an arc therein, and a single means for moving both of said conducting means; said arc drawing means causing the arc which is established within said passage of lesser arc interrupting capacity to be established subsequent to the establishing of an arc within said passage of greater arc extinguishing capacity. 125
27. In a device for interrupting an electrical circuit; solid means of a material which is capable of evolving an arc extinguishing gas when placed in proximity to an electric arc for defining the walls of a pair of arc passages; one of 130 said arc passages being so proportioned that it is capable of extinguishing arcs of large current magnitude but is incapable of extinguishing arcs of small current magnitude, and the other of said 135 passages being capable of extinguishing arcs of 140 large current magnitude. 145
28. In a device for interrupting an electrical circuit; solid means of a material which is capable of evolving an arc extinguishing gas when placed in proximity to an electric arc for defining the walls of a pair of arc passages; one of 145 said arc passages being so proportioned that it is capable of extinguishing arcs of large current magnitude but is incapable of extinguishing arcs of small current magnitude, and the other of said 150 passages being capable of extinguishing arcs of 150

- small current magnitude; and arc drawing means for causing the circuit when carrying currents of large magnitude to be finally interrupted in the first of said passages, and for causing the circuit when carrying currents of small magnitude to be finally interrupted in the second of said passages; said arc drawing means including two separate conducting means one of which is movable through each of said arc passages to establish an arc therein, and a single means for moving both of said conducting means.
28. In a device for interrupting an electrical circuit; solid means of a material which is capable of evolving an arc extinguishing gas when placed in proximity to an electric arc for defining the walls of a pair of arc passages; one of said arc passages being so proportioned that it is capable of extinguishing arcs of large current magnitude but is incapable of extinguishing arcs of small current magnitude, and the other of said passages being capable of extinguishing arcs of small current magnitude; and arc drawing means for causing the circuit when carrying currents of large magnitude to be finally interrupted in the first of said passages, and for causing the circuit when carrying currents of small current magnitude to be finally interrupted in the second of said passages; said arc drawing means including two separate conducting means one of which is movable through each of said arc passages to establish an arc therein, and a single means for moving both of said conducting means; each of said arc passages having a cross-sectional area only slightly greater than the conducting means movable therethrough during the operation of said interrupter.
29. In a device for interrupting an electrical circuit; solid means of a material which is capable of evolving an arc extinguishing gas, substantially all of which is non-inflammable, when placed in proximity to an electric arc for defining the walls of a pair of arc passages; one of said arc passages being so proportioned that it is capable of extinguishing arcs of large current magnitude but is incapable of extinguishing arcs of small current magnitude, and the other of said passages being capable of extinguishing arcs of small current magnitude; means operable upon the occurrence of predetermined conditions to draw an arc within said passage of large arc extinguishing capacity; and means for causing arcs of small current magnitude to be transferred to said other arc passage subsequent to the drawing of an arc within said passage of large
- 5 55 60 65 70 75
- arc extinguishing capacity; said arc drawing and said transferring means comprising two separate conducting means one of which is movable within each of said arc passages, and a single means for moving both of said conducting means.
30. In a device for interrupting an electrical circuit; a single wall defining means having a pair of arc passages therein; one of said arc passages being so proportioned that it is capable of extinguishing arcs of large current magnitude but is incapable of extinguishing arcs of small current magnitude, and the other of said passages being capable of extinguishing arcs of small current magnitude; conducting means movable through each of said arc passages upon the occurrence of predetermined conditions to draw an arc therein; a single spring means for moving both of said arc drawing means; and means comprising a lost motion mechanical connection for causing one of said arc drawing means to be moved through said other arc passage subsequent to the drawing of an arc within said passage of large arc extinguishing capacity.
31. In a device for interrupting an electrical circuit; a single means of a material which is capable of evolving an arc extinguishing gas, substantially all of which is non-inflammable, when placed in proximity to an electric arc for defining a pair of arc passages having rigid walls; one of said arc passages being so proportioned that it is capable of extinguishing arcs of large current magnitude but is incapable of extinguishing arcs of small current magnitude, and the other of said passages being capable of extinguishing arcs of small current magnitude; means operable upon the occurrence of predetermined conditions to draw an arc within said passage of large arc extinguishing capacity; and means for causing arcs of small current magnitude to be transferred to said other arc passage subsequent to the drawing of an arc within said passage of large arc extinguishing capacity; said arc drawing and said transferring means comprising two separate conducting means one of which is movable within each of said arc passages, a single means for moving both of said conducting means, and a lost motion connection intermediate said moving means and one of said conducting means; each of said arc passages having a cross-sectional area only slightly greater than the conducting means movable therethrough during the operation of said interrupter.
